VAPORIZER

Harry Avrigan, Jr., Ambler, Pa.

Application December 17, 1952, Serial No. 326,475

4 Claims. (Cl. 219—19)

1

My invention relates to vaporizers, and it relates more particularly to devices for electricity heating a vaporizable substance.

The need for an adequate vaporizer has resulted in various attempts being made to supply such a device. These have not performed adequately or satisfactorily however, for electrically heated vaporizers thus far constructed have generally proven wasteful of electric current, and wasteful of charge of vaporizing substance, particularly when it is desired to remove an unused portion of the charge from the vaporizer in order to save it for a later use; and the nature of the vaporizers thus far supplied has generally been such as to render the vaporizer subject to loss or to breakage.

One object of my invention therefore is to provide a vaporizer which is so constructed as to consume electric current substantially only while it is charged with a vaporizable substance.

Another object of my invention is to provide a vaporizer which is so constructed as to render readily interchangeable various vaporizing charges, and in a manner to preserve unused portions of the charges during their removal from the vaporizer.

A further object of my invention is to provide a vaporizer which may be permanently installed in a room, and in a minimum of space therein, while being so constructed as to eliminate the possibility of loss, and reduce to a minimum the occurrence of breakage.

Another object of my invention is to provide a vaporizer which is so constructed that it may form a permanent unit in a vaporizing system wherein a plurality of rooms in a building may each be supplied with one such unit, and the entire building may be quickly, readily and efficiently serviced at regular intervals by replacing vaporizable charges at said intervals.

A further object of my invention is to provide a vaporizer which is so constructed that possibility of undesired electrical contact or shock while replacing vaporizable charges, is eliminated.

With the above and other objects in view, my invention consists of a vaporizer comprising a housing adapted to be permanently installed on a wall of a room, a chamber pivotally mounted on said housing, a plurality of spaced electrical contact members disposed in said chamber, each of said contact members comprising a receptacle portion and a bearing portion, a plurality of contact elements mounted in said housing, each of said contact elements being disposed within the path of rotation of one of said bearing portions when said chamber is

2

moved about its pivotal mounting; and a vaporizable charge comprising an electrical resistance wire, an electrical contact device electrically connected to said wire at one portion thereof, and an electrical contact device electrically connected to said wire at another portion thereof, and a vaporizable substance disposed about said resistance wire and mounted between said electrical contact devices, said electrical contact devices being spaced a distance substantially equal to the distance between said receptacles, and being adapted to be readily inserted into and removed from said receptacles; said resistance wire having a current-usage life which is substantially equal to the time required to sublimate the vaporizable substance at the temperature generated by said resistance wire when a normal flow of electrical current is passed therethrough; and said chamber comprising channels for the passage of air therethrough and about said vaporizable charge.

For the purpose of illustrating my invention, I have shown in the accompanying drawings forms thereof which are at present preferred by me, since the same have been found in practice to give satisfactory and reliable results, although it is to be understood that the various instrumentalities of which my invention consists can be variously arranged and organized and that my invention is not limited to the precise arrangements and organizations of the instrumentalities as herein shown and described.

Referring to the drawings in which like reference characters indicate like parts:

Figure 1 represents a front elevational view of a vaporizer embodying my invention.

Figure 2 represents a vertical section view taken generally along the lines 2—2 of Figure 1, and embodying my invention.

Figure 3 represents an extended vertical sectional view, partly fragmentary, of a vaporizer showing the same in open condition ready for receiving a vaporizable charge, and embodying my invention.

Figure 4 represents a prospective view, partly broken away, of a vaporizer, showing the same in open condition and ready to receive a vaporizable charge, and embodying my invention.

Figure 5 represents a vertical sectional view of a vaporizable charge embodying my invention.

Figure 6 represents an electrical diagram showing one form of circuit embodying my invention.

According to my invention, I provide a housing 40 which may conform substantially to the usual construction of the housing of a standard switch box customarily used for mounting an electric switch on the wall of a room. Indeed, inasmuch

as my invention is adapted, in one modification thereof, for use in conjunction with a room switch, I have illustrated this modification of my invention in the accompanying drawings. Thus, the housing 10 is so constructed as to fit inside the room wall 11 and to be covered by a suitable face plate 12 which is secured to the housing 10 in any suitable manner, such for instance as the screw 13. One portion of the housing 10, such for instance as the lower part, may contain switch mechanism 14 having a finger release 15 extending through and forwardly of the face plate 12.

A chamber 16 is moveably mounted with respect to the housing 10 and base plate 12. Thus, hinge elements 17 may be disposed on the face plate 12, and carry trunnions 18 disposed on the chamber 16, preferably substantially along the lower edge 19 thereof.

The chamber 16 comprises a substantially centrally disposed bed portion 20 extending between laterally spaced end walls 21 and 22, and preferably diverging walls 23 and 24 extending between said end walls 21 and 22, and from said bed portion 20 to a peripheral rim 25. The rim 25 may comprise the coplanar edges of the end walls 21, 22 and diverging walls 23, 24, which edges are spaced from the bed portion 20. The hinge elements 17 may comprise a forward edge 26 which is so disposed with respect to the axis of the trunnions 18 that the angle between said trunnion, edge 26 and the horizontal, is complementary to the angle between the divergent wall 24 and the vertical, when said chamber 16 has been rotated about said trunnions 18 outwardly away from the face plate 12 and to the lowermost position of said chamber 16. Thus, when in said lowermost position, the wall 24 bears against the outer edges 26 of the hinge devices 17 operably to prevent further downward rotation of the chamber 16. If desired, other means (not shown) may be used for limiting said downward rotation; and also if desired, the limiting means may be so related to the chamber 16 that when the chamber 16 is in its lowermost position, the peripheral edge 25 may be disposed at an angle to the horizontal. The divergent walls 23 and 24 preferably comprise channels 27 adapted to pass air or vapor therethrough. Thus, the channels 27 may consist of louvers, or a screen (not shown), or other suitable openings.

Electrical contact members 28 are provided in the chamber 16 and are preferably spaced therein a suitable distance. Each contact member 28 comprises a base portion 29, a receptacle portion 30 and a bearing portion 31, with the receptacle portion 30 and bearing portion 31 in electrical communication. The base portion 29 is mounted on a suitable insulation block 32 which in turn is secured to the bed portion 20 by any suitable means such for instance as the screws 33. The bearing portion 31 extends through the chamber 16 and beyond the rim 25 a suitable distance, terminating in a contact wiper portion 34 which is adapted to traverse an arc about the longitudinal axis of the trunnions 18 when the chamber 16 is lifted from its lowermost position as illustrated in Figure 3 to its uppermost position wherein the rim 25 substantially bears against the outer face 35 of the face plate 12, as illustrated in Figure 2. The face plate 12 is slotted as at 36 to permit passage therethrough of the bearing portions 31 during the transition between the lowermost and uppermost positions of the channel 16.

Contact elements 37 are mounted on the hous-

ing 10 by any suitable means such for instance as the insulation base 38 secured to the contact element 37 by a suitable binding post 39 while the insulation base 38 is mounted on the housing 10 in any suitable manner. One contact element 37 may be provided for each bearing portion 31, and is disposed within the path of travel of said bearing portion 31 as said portion 31 is being inserted within the housing when the chamber 16 is lifted to its uppermost position. The wipers 34 are so shaped with regard to the contact elements 37 that they are deflected on initial contact during said upward motion, and then permitted to return toward normal position, so as releasably to interlock with the elements 37. Thus, the bearing portions 31 may consist of brass, bronze or other elastic electrical conductor. If desired, an insulating sleeve 39 may be disposed about the bearing portions 31 from the vicinity of the bed 20 to proximity to the wiper portions 34.

A vaporizable charge 40 is provided, comprising an electric resistance wire 41 extending between, and in electrical contact with, suitable contact devices 42 which may if desired be in the nature of metal caps. A suitable vaporizable substance 43 is disposed about the wire 41 and between the contact devices 42. The contact devices 42 are of a size and configuration to permit them to be readily inserted within the receptacles 30. Thus, the receptacles 30 may comprise spring clips having jaws 44 which are flared away from each other at their outer ends but which immediately behind their flared portions, may be spaced a distance less than the diameter of the cap 42, while the jaws 44 are formed substantially arcuate between the base 29 and said flared portions, with the diameter of their arc being preferably slightly less than the diameter of the caps 42. The caps 42 are preferably spaced a distance sufficient to enable them to be disposed in electrical contact with the receptacles 30 when the charge 40 is inserted within the chamber 16 and in alignment with said receptacles 30.

The vaporizable charge 43 may consist of a self-sublimating substance such for instance as camphor, dichlorobenzene or other desired solid having substantially similar properties; or it may consist of a liquid or vaporous impregnation of a porous solid such for instance as pumice, sandstone, or suitable porous ceramic. In either event, the solid, which may be referred to in the drawings by the reference numeral 45, is channeled as at 46 to permit passage therethrough of the resistance wire 41 without exposure of said wire 41 to external contact. The solid 45 may also be recessed at its end portions to receive and to hold the contact caps 42 which are in electrical communication with the resistance wire 41. The solid 45 extends intermediate the contact caps 42 and about the resistance wire 41 in a manner to provide a handle surface 47 which is adapted to permit gripping of the charge 40 between the fingers in the operations of insertion or removal of the charge from the chamber 16 and the contact members 28, and also to serve as a vaporizing surface when the vaporizable substance 43 is heated by radiation from the electrically charged wire 41, and the vapor from the substance 43 is thereby activated and dispersed from the solid 45. The vaporizable substance 43 may consist of any desired material, such for instance as a deodorant, medication, insecticide or insect repellent, perfume, or the like.

A suitable switch device 48 may be provided,

with a suitable knob or other handle means 49 for electrically connecting the contact elements 37 to the house current which is led to the device by contacts 50 and 51. If desired, a suitable signal device, such for instance as the electric light bulb 52 may be provided on the face plate 12 and in series with the circuit between one of the contact elements 37 and one of the contacts 50, 51.

The resistance wire is preferably chosen as to its current-usage life to provide that it will burn out when sufficient current has been passed therethrough to provide approximately sufficient thermal units to evaporate the given quantity of vaporizable substance 43 disposed about the resistance wire 41 in the charge 40. Thus, when for instance the charge 40 contains a quantity of vaporizable substance 43 which will fully evaporate at the end of 80 hours when subjected to a temperature of 250 degrees for that length of time; the resistance wire 41 is provided of a material, thickness and length, which will generate 250 degrees of temperature when subjected to a voltage of 110 degrees, and which will burn out when subjected to said voltage for approximately 80 hours. As a result, when the vaporizable substance 43 has substantially all been evaporated from the charge 40, the resistance wire 41 will burn itself out.

Alternatively, and particularly when the solid 30 45 itself constitutes the vaporizable substance 43, the resistance wire 41 may be chosen to burn itself out when in contact with the atmosphere. Thus, when the substance 45 has been vaporized to such an extent that a substantial gap or gaps 35 will appear between the surface 46 and the resistance wire 41, the atmosphere will directly contact the resistance wire 41, thereby oxidizing it to the extent that it will burn itself out.

In either event the flow of electric current 40 will cease when the vaporizable substance 43 has substantially fully passed from the charge 40 to the atmosphere. While current is flowing and the charge is vaporizing as a result of the heat generated thereby, the signal light 52 will glow. When the charge has fully vaporized, or when the switch 48 is in "off" position, or when no charge 40 is disposed in the chamber 16, no current will flow through the vaporizing circuit, and the signal light 52 will be off. Only when the switch 48 is in "on" position, and a charge 40 45 is disposed in the chamber 16 with its caps 42 disposed in the receptacles 30, while vaporizable substance 43 is still available for vaporizing, may current flow through the vaporizing circuit.

As illustrated in Figure 6, the vaporizing circuit A may consist of the series of contact 50, switch 48, contact element 37, bearing 31, receptacle 30, caps 42 and resistance wire 41 of the vaporizable charge 40, second receptacle 39 with its bearing element 31, and second contact element 37, signal light 52 and contact 51. If desired, the switch 14 and room lights or other electrical devices 53 may be connected in parallel with the vaporizing circuit as illustrated in Figure 6.

In operation, the chamber 16 is moved to its lowermost position as illustrated in Figures 3 and 4, and the charge 40 is inserted therein with the cap members 42 disposed within the receptacles 30. The chamber 16 is then lifted to its uppermost position, and in the process of lifting, the bearings 31 pass through the channels 36 of the face plate 12 and interlock with the contact elements 37 and in electrical com-

munication therewith. The switch 48 may then be turned into "on" position whenever it is desired to start the vaporizing operation. When this is done, current will flow through the vaporizing circuit and the signal light 52 will be illuminated while the resistance wire 41 is heated and the heat thereof causes vaporization of the substance 43. The louvers 27 permit convection of atmospheric air through the chamber 16 in a manner to draw the vaporizing substance out of the chamber 16 and into the atmosphere of the room. When it is desired to stop the vaporizing action, the switch 48 need merely be turned to "off" position.

Alternatively, when it is desired to stop the vaporizing action, the chamber 16 may be moved to its lowermost position thereby breaking contact of the bearing 31 with the contact elements 37. Also, if desired, the partially used charge 40 may be lifted out of the chamber 16 and the chamber again moved to its uppermost position. In the latter case, it will be noted that although the bearings 31 will be interlocked with the contact elements 37, no current will flow. Also, in this case, the partially used charge 40 25 may be kept in a safe place and reinserted in the chamber 16 whenever it is desired to use its vaporizable substance again. When the vaporizing substance 43 has been fully vaporized in the chamber 16, it may be left in place until it is desired to replace the charge 40, without harming any of the elements of the device, for no current will flow through the circuit.

In cases where a plurality of rooms in a building are each equipped with one of these vaporizers, the building may be regularly serviced by replacing worn-out charges 40 with fresh vaporizable charges, and the process of servicing consists merely of lowering the chamber 16, pulling out the charge 40 by means of its handle portion 47, and inserting in its place a fresh charge, and then lifting the chamber 16 to its uppermost position. Where the vaporizer is being used in rooms which require constant vaporizing action, as for instance in a room which requires the constant presence of a deodorant or an insect repellent, the servicing of the vaporizer can be timed to concur with the expiration of the predetermined life of the resistance wire 41.

Moreover, it will be noted that in the operation of replacing vaporizable charges 40, or in any operation entailing the opening of the chamber 16, the possibility of flow of current is automatically broken, and it is impossible to receive a charge of electricity by contact with any of the conductors carried by the chamber 16, whether the conductors be the receptacle 30, bearings 31, wiper blades 34, or otherwise. Nor is there any possibility of dislodging the charge from its proper place in the chamber 16 when the bearings 31 are being brought into electrical communication with the contact elements 37, the receptacles 30 serving to hold the charge 40 in place, and the trunnions 18 serving to guide the chamber 16 with its bearings 31 through predetermined paths of movement until the chamber 16 is itself closed by its rim 25 being brought into juxtaposition to the cover plate 12. It is to be understood further that the end walls 21 and 22 may serve as finger holds for use in gripping the chamber 16 and moving it between its uppermost and lowermost positions.

I am aware that the invention may be embodied in other specific forms without departing

from the spirit or essential attributes thereof, and I therefore desire the present embodiments to be considered in all respects as illustrative and not restrictive, reference being had to the appended claims rather than to the foregoing description to indicate the scope of the invention.

Having thus described my invention, what I claim as new and desire to obtain by Letters Patent is:

1. A vaporizer comprising a housing; a chamber mounted on said housing for movement within a restricted path; a plurality of spaced electrical contact members disposed in said chamber; at least one of said contact members comprising a receptacle portion and a bearing portion; a contact element mounted in said housing; said contact element being disposed within the path of movement of said bearing portion; and a vaporizable charge comprising a handle portion comprising a vaporizing surface, an electrical resistance wire disposed within said handle portion; an electrical contact device mounted on one part of said handle portion and electrically connected to one portion of said wire, and an electrical contact device mounted on another part of said handle portion and electrically connected to another portion of said wire, said handle portion comprising a material at least a part of which includes a vaporizable substance disposed about said resistance wire; and said electrical contact devices being spaced a distance substantially equal to the distance between said receptacles, and being adapted to be readily inserted into and removed from said receptacles; said resistance wire having a life which is substantially equal to the time required to vaporize said vaporizable substance at the temperature generated by said resistance wire when a normal flow of electrical current is passed therethrough; and said chamber comprising channels for the passage of air therethrough and about said vaporizable charge.

2. A vaporizer comprising a housing; a chamber mounted on said housing for movement within a restricted path; a plurality of spaced electrical contact members disposed in said chamber; at least one of said contact members comprising a receptacle portion and a bearing portion; a contact element mounted in said housing; said contact element being disposed within the path of movement of said bearing portion; a cover mounted on said housing and substantially covering said contact element from external contact, a channel passing through said cover and within said path of movement of said bearing portion, and adapted to permit passage therethrough of said bearing portion; and a vaporizable charge comprising a handle portion comprising a vaporizing surface, an electrical resistance wire disposed within said handle portion; an electrical contact device mounted on one part of said handle portion and electrically connected to one portion of said wire, and an electrical contact device mounted on another part of said handle portion and electrically connected to another portion of said wire, said handle portion comprising a material at least a part of which includes a vaporizable substance disposed about said resistance wire; and said electrical contact devices being spaced a distance substantially equal to the distance between said receptacles, and being adapted to be readily inserted into and removed from said receptacles; said resistance wire having a life which is substantially equal to the time required to vaporize said vaporizable substance

at the temperature generated by said resistance wire when a normal flow of electrical current is passed therethrough.

3. A vaporizer comprising a housing; a chamber mounted on said housing for movement within a restricted path; a plurality of spaced electrical contact members disposed in said chamber; at least one of said contact members comprising a receptacle portion and a bearing portion; a contact element mounted in said housing; said contact element being disposed within the path of movement of said bearing portion; a cover mounted on said housing and substantially covering said contact element from external contact, a channel passing through said cover and within said path of movement of said bearing portion, and adapted to permit passage therethrough of said bearing portion; and a vaporizable charge comprising a handle portion comprising a vaporizing surface, an electrical resistance wire disposed within said handle portion; an electrical contact device mounted on one part of said handle portion and electrically connected to one portion of said wire, and an electrical contact device mounted on another part of said handle portion and electrically connected to another portion of said wire, said handle portion comprising a material at least a part of which includes a vaporizable substance disposed about said resistance wire; and said electrical contact devices being spaced a distance substantially equal to the distance between said receptacles, and being adapted to be readily inserted into and removed from said receptacles; said resistance wire having a life which is substantially equal to the time required to vaporize said vaporizable substance at the temperature generated by said resistance wire when a normal flow of electrical current is passed therethrough; and said chamber comprising channels for the passage of air therethrough and about said vaporizable charge; a signal device connected in series with said contact element, and adapted to indicate the flow of current through said contact element.

4. A vaporizer comprising a housing; a chamber mounted on said housing for movement within a restricted path; a plurality of spaced electrical contact members disposed in said chamber each comprising a receptacle portion, and at least one of said contact members comprising a bearing portion; a contact element mounted in said housing; said contact element being disposed within the path of movement of said bearing portion; a cover mounted on said housing and substantially covering said contact element from external contact, a channel passing through said cover and within said path of movement of said bearing portion, and adapted to permit passage therethrough of said bearing portion; said cover being itself disposed in said path of movement of said chamber and adapted to cover the interior thereof from external contact when said bearing portion is in electrical connection with said contact element; and a vaporizable charge comprising a handle portion comprising a vaporizing surface, an electrical resistance wire disposed within said handle portion; an electrical contact device mounted on one part of said handle portion and electrically connected to one portion of said wire, and an electrical contact device mounted on another part of said handle portion and electrically connected to another portion of said wire, said handle portion comprising a material at least a part of which in-

cludes a vaporizable substance disposed about said resistance wire; and said electrical contact devices being spaced a distance substantially equal to the distance between said receptacles, and being adapted to be readily inserted into and removed from said receptacles; said resistance wire having a life which is substantially equal to the time required to vaporize said vaporizable substance at the temperature generated by said resistance wire when a normal flow of electrical current is passed therethrough.
